UNITED STATES PATENT OFFICE.

MATTHEW H. MERRIAM, OF LEXINGTON, MASSACHUSETTS.

PIPING.

SPECIFICATION forming part of Letters Patent No. 270,965, dated January 23, 1883.

Application filed November 20, 1882. (No model.)

To all whom it may concern:

Be it known that I, MATTHEW H. MERRIAM, of Lexington, county of Middlesex, State of Massachusetts, have invented an Improvement in Piping, of which the following description, in connection with the accompanying drawing, is a specification.

My invention relates to leather piping or edging, and has for its object to produce a piping which can be used equally well in straight and curved work.

When an ordinary piece of piping consisting of a strip of leather folded lengthwise and having its unfinished edge inserted between two layers of leather is to be bent to enable an article having curved or square edges to be finished by a piece of piping having a rounded edge, the rough or unfinished edge of the piping laid between the two pieces of leather or fabric the edges of which are to be finished is thrown into plaits as the piping is bent, and the unfinished plaited edge has to be skived in order to remove the projecting plaits and bring it to the proper thickness to enable it to be laid evenly between the two layers of material for which the rounded part of the piping is to form the finish. When the rounded edge of the piping has to follow the concaved edges of a piece of leather or fabric the unfinished edge of the piping has to be cut in order to permit the piping to be bent to conform to such a curve.

Piping as heretofore made has had its unfinished edge toothed or serrated by removing from it a series of triangular pieces, thus enabling it to be bent about either convexed or concaved curves without difficulty; but such piping is open to the objection that along the straight portions—which are by far the larger part of its length when in use—the removal of the triangular pieces fails to afford the proper support for the material above and below the piping, and when ordinary piping without the serration is employed it has to be cut by hand at the curved portions, thus requiring a very considerable expenditure of time on the part of the operator and loss of work of the sewing-machine which stitches the piping in place. I have been enabled to obviate these difficulties, and to produce a piping having the advantages of the ordinary unnotched piping

along the straight portions of material to be finished by the piping, and which may be curved without difficulty in either direction. I accomplish this desired object by slitting the piping from its unfinished edge at right angles to its length, and at short intervals throughout its length, the said slits merely separating the material of the piping, without removing any portion thereof, and making, as it were, a series of adjacent tongues along the unfinished edge of the piping, or that edge which is to be concealed between the material to be piped. These tongues, when inclosed between layers of leather or fabric being piped and having straight edges, will abut together, and the unfinished edge will form a continuous uniform support for the layers of material at each side and for the reception of the stitches, and no difference is observable in the effect from that produced by ordinary uncut piping. When the piping is being applied to material having convexed edges the finished edge of the piping is given a convexed curvature, and the said tongues are caused to slightly overlap one another, thus preventing plaiting or fulling of the edge or objectionable thickening. In being applied to edges having concaved curvature the said tongues permit perfect freedom of curvature, and more nearly fill the space than do the triangular tooth-like portions of ordinary serrated piping.

The drawing represents a piece of piping embodying this invention, a portion of the piping being straight and other portions being concaved and convexed.

The piping *a* is made, in the usual manner, of a strip of leather or other suitable material folded lengthwise to produce a finished edge, *a'*, and leave a rough or unfinished edge, *b*, to be included between two or more layers of fabric or leather, with the said finished portion *a'* projecting and forming the edge of the completed article. When folded the leather is pasted together. The rough edge *b* is provided with a series of transverse slits, 3, throughout its entire length, thus separating it into a series of small narrow tongues, but without removing any portion of the material. By thus slitting the unfinished edge it is possible to bend the piping around corners or curves, as shown at 4 and 5, without produc-

ing any objectionable plaiting or fulling of either edge of the said piping, as would be the case if the said unfinished edge were left intact. In passing around a convexed corner or 5 curve the said tongues are slightly overlapped, as shown at 4, and in passing around a point of concaved curvature they open out or separate, as shown at 6, while in the straight or slightly curved portions the piping lies between the layers of fabric, with substantially the same effect as if not cut at all.

I claim—

The piping composed of a strip of material

folded longitudinally to produce a finished and unfinished edge and provided with a series of 15 transverse slits extending in from the said unfinished edge, substantially as and for the purpose described.

In testimony whereof I have signed my name to this specification in the presence of two 20 subscribing witnesses.

MATTHEW H. MERRIAM.
